PROPELLING CARTRIDGE FOR
PROJECTILES

Edgar William Brandt, Paris, France

Application March 22, 1935, Serial No. 12,502
In France April 5, 1934

8 Claims. (Cl. 102—12)

This invention relates to propulsive cartridges for use in connection with mortar projectiles.

Projectiles adapted to be fired from mortars are already known which are provided with stabilizing tails and with propulsive cartridges which fit around that portion of the tail which is comprised between the body of the projectile and the stabilizing surfaces, and which can be placed in position on said tail. In this known type of projectile however, said cartridges are constituted by annular cases containing the powder and, in order to enable such cartridges to be placed in position, the tail of the projectile must be previously detached from the body, so that the cartridge can be threaded over the front end of the tail, which latter has then to be screwed onto the projectile.

The present invention aims at providing a propulsive cartridge which, whilst preserving a substantially circular form, can be placed directly around the projectile without requiring the tail to be detached beforehand.

To this end, the cartridge of the invention is subdivided into constituent charges, and is constructed after the manner of an elastic arch, the constituent charges composing the arch being attached together by elastic connections in such a manner that the arch is capable of resilient expansion, to fit above the stabilizing fins and to grip the stabilizing tail when in position.

Further features and advantages of the invention will become apparent from the following description:

In order more clearly to understand the invention, reference is made to the accompanying drawing, which illustrates diagrammatically and by way of example one embodiment thereof, and in which:

Fig. 1 is an axial section of the rearward portion of a winged projectile carrying a propulsive cartridge according to the invention, and

Fig. 2 is a section, on a larger scale, along the line 2—2 of Fig. 1.

In the embodiment shown, the body 1 of a projectile is prolonged, in the rearward direction, by a tail 2, on the extremity of which are mounted fins 3.

The propulsion is effected in known manner by the aid of an ordinary cartridge 4 introduced and frictionally held in the tail 2. Lateral openings 5 are provided in the tail 2 to enable the gases to escape.

In order to increase the range of the projectile, a variable number of propulsive relays or increments, formed by a combustible casing con-

taining a supplementary charge, are disposed on the tail 2.

These relays are constituted by two or more members 6 in the form of cylindrical crown segments, with rounded ends, resembling the shape 5 of a bean, and connected together at one end 7, by a resilient or elastic fitting or reinforcement 8.

The free edges 9 of each half of the relay diverge automatically on being pushed into contact with the tail 2, and then converge again due to the elastic action of the fitting 8 when the whole is in position on the tail. The inner diameter of the relay constituted by the cylindrical crown segments is less than the external diameter 15 of the fins 3, and hence these fins prevent the relays from slipping backward off the tail.

The arrangement operates as follows:

The cartridge and the number of relays required for attaining the desired range, is placed 20 in position in the mortar and the shot is fired by the percussion of the cartridge 4. The gases escaping through the openings 5 set fire to the relays or increments 6 so that the gases from these increments or relays cooperate with those 25 of the cartridge 4 to drive the projectile, by acting on its rear face. Since the relays have been placed, not on the fins, but in front thereof, their deflagration cannot damage the fins, which are 30 consequently not exposed to any risk of distortion.

It is obvious that the invention is capable of various modifications and alterations without departing from the spirit and scope thereof as defined in the appended claims.

Having thus described my invention, what I claim as new and desire to secure by Letters Patent is:

1. A propulsive cartridge for projectiles, comprising at least two casing members for containing the propellant, and resilient means connecting the adjacent ends of said cartridge members with the exception of one pair of the adjacent ends of two such casing members which remain free, said resilient means urging the said 40 one pair of adjacent ends the one towards the other.

2. A propulsive cartridge for projectiles, comprising at least two casing members, said casing members having rounded adjacent ends and resilient means connecting the adjacent ends of said cartridge members with the exception of one pair of the adjacent ends of two such casing members which remain free, said resilient 50 55

means urging the said one pair of adjacent ends the one towards the other.

3. The combination with a projectile having a body with a tail extending rearwardly therefrom and stabilizing fins on said tail, of a propulsive cartridge comprising at least two casing members for containing the propellant, and resilient means connecting the adjacent ends of said members, with the exception of one pair of the adjacent ends of two such members which remain free, said resilient means yielding to permit the said free ends to be spread out for placing the cartridge around the tail and operating for urging the free adjacent ends one toward another for retaining the cartridge in position on the tail.

4. The combination with a projectile having a body with a tail extending rearwardly therefrom and having stabilizing fins on said tail with the forward ends of said fins terminating short of said body, of a propulsive cartridge comprising at least two casing members having substantially the form of cylindrical crown segments for containing the propellant, and resilient means connecting the adjacent ends of said members with the exception of one pair of the adjacent ends of two such members which remain free, said resilient means tending to maintain the members in the form of a cylindrical crown having an internal diameter less than the outer diameter of the fins and operating during the placing of the cartridge upon the tail of the projectile to permit said free ends to be spread out for passing around the tail, said resilient means operating to maintain the cartridge in position upon the tail.

5. The combination with a projectile having a body and a tail extending rearwardly therefrom, stabilizing fins on said tail with the forward ends of the fins spaced from said body, and a main propulsive cartridge located within said tail, the tail having passages for communicating the fire from said main cartridge, of an additional car-

tridge comprising at least two propellant members each extending for a part of the circumference of the tail, and resilient means connecting adjacent ends of one pair of said members with the exception of the adjacent ends of two such members which remain free, said resilient means urging the two free adjacent ends toward one another, said tail being provided with a sufficient number of passages for transmitting the fire from the main cartridge to all said members simultaneously.

6. A propulsive cartridge for projectiles, comprising at least two propellant elements, and yielding means connecting adjacent ends of said elements at one pair of ends, said yielding means permitting separation of free adjacent ends of said elements and normally operating to hold said free ends close together in the form of a cylindrical crown.

7. The combination with a projectile having a body and a reduced tail portion with stabilizing fins at the free end thereof, of a propulsive cartridge of annular form for embracing said tail between the body and fins, said cartridge comprising a plurality of individual propellant elements for extending around said tail portion and yielding means for joining all except one pair of adjacent ends of said elements and operating for permitting said one pair of ends to be separated to permit the cartridge to be positioned around the tail portion and for causing said ends to move toward one another and for holding the cartridge in place when so positioned.

8. A propulsive cartridge for projectiles, comprising a plurality of casing members for containing the propellant, and yielding means connecting all except one pair of adjacent ends of said casing members, said means permitting separation of the said one pair of adjacent ends and normally operating to hold said pair of ends close together.
